PACKAGING TRAY FOR COOKIES OR THE LIKE

Herman L. Dobson, 19 Fairway, Bloomfield, N.J.

Filed Oct. 19, 1961, Ser. No. 67,193

Term of patent 14 years

(Cl. D58—13)

I claim:

The ornamental design for a packaging tray for cookies or the like, as shown.
